H. W. HILL,
PROCESS OF FORMING BIFOCAL LENSES,
APPLICATION FILED JUNE 3, 1914.

1,190,242.

Patented July 4, 1916.

UNITED STATES PATENT OFFICE.

HARRY W. HILL, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

PROCESS OF FORMING BIFOCAL LENSES.

1,190,242.

Specification of Letters Patent. Patented July 4, 1916.

Application filed June 3, 1914. Serial No. 842,576.

To all whom it may concern:

Be it known that I, HARRY W. HILL, a citizen of the United States, residing at Southbridge, in the county of Worcester and State of Massachusetts, have invented certain new and useful Improvements in Processes of Forming Bifocal Lenses, of which the following is a specification.

My invention relates to improvements in bifocal lenses and has particular reference to an improved process for forming the same.

The leading object of my invention is the provision of an improved process for facilitating the satisfactory uniting of the segment and major portion of a two part bifocal lens or the like.

A further object of my invention is the provision of an improved process for inexpensively and satisfactorily uniting the said parts which will reduce to a minimum both strain in the lenses and liability of breakage thereof.

Another object of my invention is the provision of a separating member for the parts which shall be independent of both of the parts and which shall permanently unite therewith during the fusing operation and thus facilitate completion of the lens after fusion of the parts thereof.

Other objects and advantages of my improvement should be readily apparent by reference to the following description taken in connection with the accompanying drawings, and it will be understood that I may make any modifications in the specific details of construction shown and described within the scope of the appended claims without departing from or exceeding the spirit of my invention.

Figure I represents a plan view of a blank illustrating the prior art process and being so designated. Fig. II represents a sectional view on the line II-II of Fig. I. Fig. III represents a plan view of one step in my improved process. Fig. IV represents a sectional view on the line IV-IV of Fig. III. Fig. V represents a plan view of the completed blank constructed by the use of my process. Fig. VI represents a sectional view on the line VI-VI of Fig. V.

In the drawings, in which similar characters of reference are employed to denote corresponding parts throughout the several

views, the numeral 1 designates the main or major portion of a lens blank having preferably formed therein the recess or countersink 2 adapted to receive a portion of the segment 3, the major portion 1 and segment 3 being formed from glass or similar material having different indices of refraction, whereby the same curve ground on the outer faces of the major and minor portions of the lens will produce different powers in said two portions.

Prior to my invention it has been customary in forming lenses of this character to rest one edge of the segment against the major portion of the lens and to place beneath the opposite edge thereof or at a plurality of points, as may be preferred, a block 4 of steel. The lens is then subjected to sufficient heat to render the same plastic, this heat causing the segment 3 to gradually soften and flow down into and fill the recess or countersink 2, the member or members 4 holding one edge up as long as possible so that the gas and air accumulated between the segment and the face of the countersink may be expelled at this side. The operation to this extent is quite desirable and advantageous. Great difficulty has been experienced, however, on account of the presence of the steel member 4, one great disadvantage of this member being readily evident by reference to Figs. I and II, from which it will be seen that waves or distortions are occasioned as at 5 on account of the glass having to soften and flow around the member 4. These consequently destroy the utility of the glass at this point and render it necessary to cut a much smaller lens from the blank than would otherwise be the case, while rendering it absolutely impossible to provide a lens such as that indicated by the dotted lines on the blank in Fig. V, that is to say, one in which the reading portion is disposed toward the center and a distance portion is provided both above and below the segment.

Another great disadvantage of this prior art construction is the necessity for removal of the steel member before completion of the lens; this removal can only be done by in some way removing the steel member from between the two parts which are fused around it, thus entailing in practically every instance chipping and breaking off of the edge

of the segment and of the major lens, further impairing the utility of the blank so that ordinarily the useful portion of the blank is only about that indicated by the dotted lines in Fig. I.

5 My improved construction and process of forming a bifocal lens blank, however, does away with all of these disadvantages, and makes it possible to produce a lens both 10 without the wave effects and distortions present in the prior art blanks, and in all cases to at least reduce these defects to a negligible minimum and thus enables the cutting out of a lens such as indicated by the 15 dotted lines in Fig. V, or if desired the forming of two lenses from a single blank, an impossibility with the prior art form of construction.

20 A further great advantage of my improvement lies in the fact that there is no steel member present which must be broken out, and it is possible to directly grind the blank to desired curve without any portion thereof having been chipped off or broken away, 25 this being both an advantage in working the lens and reducing to a minimum liability of the expensive blank becoming broken in course of manufacture, as the blank is neither weakened by removal of 30 the member 4 or cracked in the attempt to remove the same.

35 My invention consists in the use in the old process of a member or members 6 which are formed from glass or similar material which will fuse and unite with the parts to be joined and will become an integral part thereof. By this improved process I take the major lens, form the countersink therein, place in position my wedge or wedges of 40 glass, and then mount the minor portion or segment 3 of the lens in position as indicated in Fig. IV. Upon fusing the portion 6 while serving the function of a spacing member as the segment is fused, eventually is 45 softened and melts into the segment in place of being stiff and rigid, thus eliminating entirely or reducing to a minimum any possible wave effect, such as indicated at 5 in Fig. I, while at the same time the fact that 50 this member is of glass and united with the parts permits after the fusing of the grinding of the lens without necessity of removing the spacing member and without damage to the grinding tools.

55 To further increase the efficiency of my improved process and to eliminate any possible slipping of the separating member, such as has proved itself objectionable in the case of the steel insert previously employed, I 60 may, if desired, place either on the lower blank or on my separating member a suitable adhesive which will serve to temporarily retain the separating member in position, this adhesive, however, being preferably such as to either be entirely dried off

and evaporated by the fusing action or else such as to unite with the separating member and blanks during the fusing action so that no trace of the same will be present in the completed lens, it being understood, 70 however, that in some instances other adhesives than those which will be self eliminating may be employed, according to the particular kind of lens to be made.

75 It is to be understood that while I have particularly described this process as making use of a separating member of the same material as the parts to be united, that it may in some instances be of some other material which will either evaporate or be 80 practically or entirely eliminated by the heating action, one of the essentials of my process being the feature of so uniting the parts that in the finished condition there will be no pronounced separating member, no 85 member which it is necessary to remove, and there will be no member which will cause the disagreeable and destructive wave of such which are caused by the steel member which has been in common use prior to my invention.

90 If desired, I may slightly modify my process by first cementing the separating member or members to the major lens at the desired point thereon and may anneal 95 the said major blank by raising the temperature thereof at the same time the cement so hardening as to securely retain the spacing members in position thereon. I may then suitably clean the portion of the major blank 100 or depression so as to receive the segment and most carefully prepare said portion for the reception of the segment, after which the segment may be placed in position as before described, and the complete blank raised to 105 the welding or fusing temperature.

I claim:

1. The process of uniting blanks for bifocal lenses, which consists in forming a major portion with a depression therein, mounting 110 a spacing member having an adhesive coating at one side of the depression, mounting a second blank above the depression with one side held away from the first blank by the said spacing member, subjecting the said 115 parts to a welding heat, whereby one of the blanks is caused to soften and settle down upon and unite with the spacing member and with the other blank, and grinding the resultant unitary blank into a finished 120 ophthalmic lens.

2. The process of making bifocal lenses which consists in supporting the parts to be united in spaced relation through the medium of a spacing member of the same material as the parts to be united, applying an adhesive to retain the spacing member in correct position between the parts, and subjecting the parts and spacing member to a welding heat to fuse the three parts into a 130

single unitary structure, substantially as described.

3. The process of forming an ophthalmic bifocal lens blank, consisting in forming a major portion with a depression therein, coating a spacing member with a suitable adhesive, placing the spacing member at one side of the depression, mounting a second blank on the first with one edge in engagement with the first and the other spaced therefrom by the spacing member, and subjecting the parts to a welding heat, whereby

the spacing member and one of the blanks are rendered plastic and settle down into close engagement with the other blank and 15 unite therewith in a single unitary structure.

In testimony whereof I affix my signature in presence of two witnesses.

HARRY W. HILL.
